UNITED STATES PATENT OFFICE

HARRY RANISH, OF LOS ANGELES, CALIFORNIA

MOPPING, SPREADING, AND POLISHING DEVICE

Application filed September 26, 1930. Serial No. 484,600.

An object of this invention is to provide a means adapted for use for spreading upon a floor, oil or liquid wax as may be required, and for polishing such floor; and also 5 adapted for use with slight changes for washing windows and for other various surface treating uses to which it may be found applicable.

10 Simplicity and cheapness of construction; and ease of supplying and controlling the supply of oil or liquid wax to and through the applicator, are further objects.

15 Another object is to provide a device of the character set forth having inter-changeable parts more particularly adapted for fitting the device to be used in some instances for oiling a floor, in other instances for waxing the floor; and in other instances for polishing the floor and in still further instances 20 for scrubbing floors and washing and cleaning windows and other surfaces.

25 An object is to provide a tasseled or fringed brush of particularly satisfactory exchangeability for oiling, and for waxing in some instances, and for using water for washing and scrubbing windows and floors, and for use in drying windows and other surfaces.

30 The invention is not limited to the specific construction shown, and it is understood that forms of embodiment other than those shown may be employed without departing from the invention or from the principles herein disclosed and embodied in the mechanism herein set forth and claimed.

35 Other objects, advantages and features of invention may appear from the accompanying drawing, the subjoined detailed description and the appended claims.

40 The accompanying drawing illustrates the invention.

Figure 1 is a perspective view of the device as in use for oiling a floor surface and spreading the oil thereover; the handle being broken to contract the view and the applicator reversed to expose the rear of the applicator and the brush fastening.

45 Fig. 2 is an enlarged view in vertical axial section showing the arrangement by which oil is fed from a handle reservoir to the ap-

plicator chamber; broken lines indicate a position of parts for supplying oil to the applicator chamber.

Fig. 3 is a detached detail of the brush removed. 55

Fig. 4 is a view of the detached brush handle and scraper adapted for use alone and also for application to the brush to fit it for window washing.

Fig. 5 is a view looking down into the uncapped handle of Fig. 2. 60

Fig. 6 is an enlarged section on line X6, Fig. 4.

Fig. 7 is a perspective view of the underside of the mop head with applicating chamber empty except as to the end of the oil valve tube from which its closure has been unscrewed and omitted from the view. 65

Fig. 8 is a view of the mop head with the distributing plate and pad, and the oil tube terminal closure in place; the pad being broken to expose the plate. 70

Fig. 9 is a top view of the device with adjuncts in place for applying liquid wax to a floor surface; the handle being broken away to contract the view. 75

Fig. 10 is an axial section of Fig. 9 central to the wax tube and omitting parts shown in Fig. 2 above the valve closing spring in Figs. 1, 2 and 9. 80

The hollow handle 1 is provided with a threaded socket and nipple connection as at 2, 3, to form a hinging conduit 4 that is connected by a hinging T pipe fitting 5 having its stem screwed onto a valve nozzle 6 slidingly fitted as at 7 to a head comprising a head plate 8 through which the nozzle extends to deliver liquid into a distributing chamber 9 open at the bottom and formed underneath the head plate and surrounded by a collar 10 having means, as the spring fingers 11 for securing a brush 12 to the collar and therethrough to the head plate 8. 85

The brush 12 may be of any practical construction and is shown as comprising a belt formed of a strap 13, having ties 14 and a fringe 15; the strap being adapted to fit the outside of the collar 10 and to be held thereon by the ties 14 and to be fixed in place by the fingers 11 inserted into pockets 16 in the in- 95 100

ner face of the strap 13, so that the brush forms a spreader approaching a circular form, and the fringe constitutes a normally soft floor contacting extension of the walls 5 of the chamber through which the oil or liquid wax is to be applied.

17 is a distributing plate having perforations 18 and a hole 19 through which latter the nozzle 6 reciprocably extends to intermittently apply liquid to a porous pad 20 to which oil or liquid wax may be passed; said nozzle being provided with an intermediate lateral outlet 21 that is closed in one position and opened in another position.

Resilient means as the bow spring 22 having a hole 23 in its crown, and having its feet 24 arranged to rest on the head plate 8, holds the nozzle withdrawn from the pad 20 and 20 into position where it is covered by a valved ferrule 25 which is fixed to and extends upward from the head 8 and is spaced from the crown of the spring 22 which acts against the end of the stem 26 of the T, thus to normally and yieldingly elevate the valve tube 6, to close the nozzle outlet 21, and to allow the nozzle to be removed by downward pressure on the handle at the will of the operator, thus bringing the outlet 21 into position to 30 deliver oil to the porous pad.

Said pad 20 and distributor 17 is fastened to the nozzle by washers as at 27 and 28, and by a cap 29 which is threaded onto the end of the nozzle so that the lower end of the 35 nozzle is closed and the liquid can only flow out of the nozzle through the outlet 21 when the nozzle is depressed against the force of the spring.

The hinge conduit 4 has in its head an oil 40 way 30 and a threaded valve seat 30' in which is fitted a rotary check reservoir closing valve 31 shown as provided with a passage formed by a slot 32 always open to the handle to receive oil from the handle chamber, but closed 45 to the passage 30 when the valve is turned into one position, and open to such passage when the valve is turned to another position, so that when it is not desired to allow oil to flow into the nozzle, the valve may be turned 50 to close the passage; and, vice versa, when the valve is turned contra-wise, free flow to the nozzle will be allowed and is also provided to control the flow of liquid as it may be desired.

55 Portions 33 and 34 of the collar serve as supports for the head to prevent the spring fingers 11 from being deformed by excessive down pressure on the applicator head.

For convenience in assembly, a detachable 60 conducting section 35 is provided to make connection between the oil way 30 and the passage in the T and such section is shown secured in place by means of the threaded end of the detachable section 35, and by 65 means of a fastening screw 36 extending

through such section and screwing into a threaded seat 37 in the head of the conduit 4.

38 is a cap to close the upper end of the tubular handle and when the cap is removed the handle may be charged with oil and is 70 preferably of sufficient capacity to hold more than the contents of the usual size bottle of oil or polish that is to be distributed by the brush.

The handle thus forms the oil reservoir for 75 the oil applicator.

In practical use the operator having filled the handle and opened the adjustable valve 31 for controlling the flow of liquid, will use the appliance as common in using a mop, and when he desires to feed liquid to the absorbent pad 20 he will press upon the handle to depress the spring and nozzle, thus to allow flow 80 of the liquid to the porous pad 20.

The wax reservoir 39 is shaped to afford a 85 convenient handle for the applicator and has end orifices 40 and 41 for attachment to the handle and to the nipple 3.

The device shown in Fig. 4 comprises a rubber strip 42 in a channeled holder 43, provided with a threaded stud 44 adapted to screw into the end of the handle 1 where said handle is unscrewed from the hinged conduit 4, so that when windows have been cleaned 95 the device can be used for drying the same as in common practice.

In order to store this drying contrivance for convenient use and to keep it free from oil, a case 45 having a hook 46 is provided to receive the rubber strip 42, its channeled holder 43, and the stud 44, and is adapted to slip down inside the handle 1 to allow the scraper 42, 43, 44, to be stored in the top end of the handle without coming into contact 105 with the oil therein.

In order to charge the handle with oil, the case 45 will be withdrawn and the oil poured into the end of the handle, and the case 45 returned to the handle; the cap 38 will then be 110 put into place.

The case 45 is made to fit friction tight in the handle so that it will not slip down inside the handle; and the hook 46 serves as a catch under which a nail or other instrument 115 may be inserted to withdraw the case from the handle; whereupon the scraper may be withdrawn from the case for use as above indicated.

In the form shown in Figs. 9 and 10, the applicator is provided with a felt pad 47 that 120 is secured to the collar 10 by a thimble 48 having an inwardly extending flange 49 over which is applied a porous pad 50 through which the liquid wax will flow into the pad 47, through which it passes to the floor to be 125 waxed.

The applicator is preferably of an oval form and is provided with a point 51 to enter into corners for spreading oil and polishing 130 at places in such corners.

The applicator top is shown as made of a single piece of sheet metal stamped, slit, punched, struck up, drawn and swaged to provide the head 8, the fitting 7, the collar 10, 5 the fingers 11, and the double thick strengthening top flange 52.

I claim:

1. A device of the character set forth comprising an applicator provided with a head 10 plate and a distributing chamber having an open bottom; spring fingers integral with said chamber; a distributor inside having a vertical movement; said distributor comprising an adjustable valve and a valve nozzle 15 provided with an intermediate lateral outlet that is closed in one position and open in another position to supply to said chamber the substance to be distributed and spread; a brush provided with pockets and means comprising said spring fingers to fit into said pockets for securing the brush to the outside of said chamber.
2. A device of the character set forth for connecting a hollow handle to an applicator 25 head; a conduit in hinged relation to the head and provided with an internally and externally threaded nipple for connection to the handle; said conduit provided in its head with an oil way and a threaded valve seat in 30 which is fitted a check valve; said valve provided with a passage formed by a slot always open to the handle to receive oil from the handle chamber, but closed to said oil way when the valve is turned into one position and open 35 to such passage when turned to another position and will control the flow of oil as desired by the operator.
3. In a device of the character set forth, an applicator head having an open ferrule on its 40 top side and a collar on its under side; a hollow handle connected to said applicator head; a chamber having an open bottom surrounded by the collar; a valve nozzle in the ferrule and provided with an intermediate lateral 45 outlet adapted to be open to the chamber when the valve nozzle is depressed by said handle; a porous pad mounted on said valve nozzle in the chamber; a distributing plate interposed between said pad and head; a cap 50 threaded onto the lower end of said valve nozzle; washers held in place by the cap and said washers and cap to fasten said distributing plate and pad to the valve nozzle.

In testimony whereof, I have hereunto set 55 my hand at Los Angeles, California, this 19th day of September, 1930.

HARRY RANISH.
